UNITED STATES PATENT OFFICE.

WILLIAM J. CRUMPTON, OF EVANSTON, ILLINOIS, ASSIGNOR, BY MESNE ASSIGNMENTS,
TO WILLIAM R. HEATH, OF BUFFALO, NEW YORK.

ACCOUNTING SYSTEM.

1,106,284.

Specification of Letters Patent.

Patented Aug. 4, 1914.

Application filed June 28, 1909. Serial No. 504,655.

To all whom it may concern:

Be it known that I, WILLIAM J. CRUMPTON, a citizen of the United States, residing at Evanston, in the county of Cook and State of Illinois, have invented certain new and useful Improvements in Accounting Systems, of which the following is a full, clear, concise, and exact description, reference being had to the accompanying drawings, forming a part of this specification.

My invention relates to improvements in accounting systems and has particular reference to a system for accounting the time and wages of workmen and also for distributing the wages between a plurality of jobs.

Methods have previously been employed by which the accounting registers are actuated directly by electromagnetic actuating devices. In the present invention I provide electromagnetic means by which the registers may be brought into mechanical connection with a source of power, this source preferably consisting in a rotating shaft.

It is evident that two general methods might be used to accomplish the desired result: First, the speed of the rotating shaft or shafts could be made constant and the accounting registers brought into mechanical connection with the shafts for a length of time proportional to the amount which it is desired to actuate the registers; in which case the total operating period may be divided into operating increments of fixed length and variable number, or vice versa; second, the registers could be brought into mechanical connection with the shafts for a fixed length of time, and the speed of the various shafts could be regulated according to the amounts which it is desired to actuate the registers in a given time. In the present application, I shall describe means by which the first of these general methods may be carried into execution.

The general system of controlling electrical circuits used in the present invention is much the same as that employed in my copending application, Serial No. 437,809 filed June 11, 1908, the present improvement consisting in providing driving apparatus and apparatus for connecting the registers with said driving apparatus which as here shown consists of a series of shafts driven at constant speed for a length of time

proportional to the time which an individual workman is employed or proportional to the amount of wages which he earns.

The advantages of my invention will be more apparent by reference to the accompanying drawings, in which—

Figure 1 is a diagrammatic representation of my system as a whole, Fig. 2 is a plan view of the electromagnetic clutch actuating mechanism, and Fig. 3 is a sectional view on the line 3—3 of Fig. 2.

In order that the operation of my system as a whole may be more clearly understood, I will first describe the detailed construction of the electromagnetic mechanism which actuates the clutch by means of which the accounting register is connected with a mechanical source of power, for example, a shaft.

Referring to Figs. 2 and 3, 1 and 2 are the windings of an electromagnet having cores 3 and 4 respectively, these cores being rigidly attached to the frame 5 by means of the screws 6 and 7 respectively. On these ends the cores 3 and 4 are connected by means of the magnetic yoke 8. Attached to the yoke 8 by means of the screw 9 is a permanent magnet 10, formed at its free end into the semicircular portion 10^a. The working ends of the cores 3 and 4 are formed into members 11 and 12 which, as shown in Fig. 2, have their faces parallel and opposite to each other.

A shaft 13 of non-magnetic material passes through the members 11 and 12 which act as bearings for the shaft, lateral movement of the same being prevented by means of collars 14 and 15. A clutch 16 is mounted on the shaft 13 between the members 11 and 12. A key 17 is securely mounted in the shaft 13 and loosely fits in a keyway 18 in the clutch 16. It is thus evident that lateral movement of the clutch 16 is possible between the collars 14 and 15, mounted on the shaft 13, but the clutch 16 cannot be rotated with respect to the shaft 13 itself. The clutch 16 is divided into two lateral portions, first, an idler portion 19 on the outer side of which is the flange 20; and second a portion 21 which is provided with two teeth 22 diametrically opposite to each other. A flange 23 similar to the flange 20 is provided on the outer side of the portion 21. A register 24 is securely mounted on

the member 12 and held in position by the screw bolts 25 and nuts 26 which pass through suitable projections from the register 24 and the member 12. Rigidly mounted 5 on the actuating shaft 27 of the register 24 is a gear 28 which, when the clutch 16 is moved to the right, as shown in Fig. 2, against the collar 15, would be adapted to engage the teeth 22 on the portion 21 of the 10 clutch 16. On the other hand, when the clutch 16 is moved to the left against the collar 14, the gear 28 would be opposite the idler portion 19 of the clutch member 16, and would, therefore, not be rotated by the 15 rotation of the clutch member.

The operation of this device may now be clearly understood. The shaft 13 may be constantly rotated at a predetermined speed. Let us now assume that it is desired to actuate the register 24. The windings 1 and 2 are energized and the pole members 11 and 12 are given a polarity which will attract the clutch 16 to the right against the collar 15 as the shaft 13 rotates, the gear 28 will 20 be moved two steps, on account of the actuation by the two teeth 22 of the clutch 16, on each rotation of the shaft 13. When it is desired to disconnect the clutch from the gear 28, the polarity of the poles 11 and 12 is reversed and the clutch 16 is thereby attracted to the left against the collar 14. The portion 10^a of the permanent magnet 10 causes a permanent magnetism in the clutch 16 of such nature that the attraction or 25 repulsion of the clutch by the poles 11 and 12 is brought about.

We now turn to the operation of the system as a whole, as illustrated in Fig. 1. Rigidly mounted on a shaft 29 are the 30 pulse-making disks of electrically conducting material 30, 31, 32 and 33. The disk 30 is provided with an insulating segment 34 and the disk 31 has an insulating segment 35, the insulating segment 35 of the disk 31 35 occupying a relative position slightly overlapping the conducting portion of the disk 30. An insulating section 36 is placed on the shaft 29 between the disks 31 and 32. The disk 32 has an insulating segment 37 40 in the same relative position as the segment 34 of the disk 30, and the disk 33 has an insulating segment 38 in the same relative position as the insulating segment 35 of the disk 31. Connected to one pole of a battery 39 is a conductor 40 which joins a second conductor 41 at the point 42. One end of the conductor 41 is connected to the brush 43 which bears on the periphery of the disk 30. The other end of the conductor 41 is 45 connected to the brush 44 which bears on the periphery of the disk 33. A conductor 45 is connected to the second pole of the battery 39 on one end, and on the other end is connected to the brush 46 which bears on the periphery of the disk 32. A conductor 47

leads from the conductor 45 to the brush 48 which bears on the periphery of the disk 31.

Rigidly mounted on the shaft 29, and in electrical connection with the impulse making disks 32 and 33, are the rate disks 49, 50, 51 and 52. These disks are provided with insulating segments 49^a, 50^a, 51^a and 52^a, which insulate different lengths of the peripheries of the disks 49, 50, 51 and 52 respectively. Bearing on the periphery of each disk is a brush 53 which is connected by means of a conductor 54 with the contacts of a series of jacks. The jacks associated with the rate disk 49 are represented as 55; those associated with the disk 50, as 56; with the disk 51, as 57; and with the disk 52, as 58. As will be explained more in detail hereafter, each of these series of disks represents a predetermined rate of wages.

Rigidly mounted on suitable frameworks 55 are the segmented selecting commutators 59 and 60. Rigidly mounted on a shaft 61 are the brush holders 62 and 63, holding the brushes 64 and 65 which are adapted to simultaneously make contact with the corresponding segments of the selecting commutators 59 and 60. Also rigidly mounted on the shaft 61 is a gear 66 insulated from the selecting commutators 59 and 60 by means of an insulating section 67 on the 90 shaft 61. Rigidly mounted on the shaft 29 is the disk 68 provided with the tooth 69 adapted to coöperate with the gear 66. The disk 68 is insulated from the disks 49, 50, 51 and 52 mounted on the same shaft by means of the insulating section 69^a of the shaft 29. It is now clear that as the shaft 29 is rotated one revolution, the tooth 69 of the disk 68 will cause the gear 66 to be advanced one step.

The selecting commutators 59 and 60 are composed of alternating conducting segments 70 and insulating segments 71, these segments being so spaced that when the gear 66 is advanced one step, the brushes 64 and 65 will be moved from one conducting segment to the next adjacent conducting segment. The number of these conducting segments corresponds to the number of workmen whose time and wages can be accounted for by this system.

In Fig. 1, it has been assumed that six workmen, A, B, C, D, E and F are employed and the conducting segments have been correspondingly designated according 120 to these letters. To each of the conducting segments of the selecting commutator 60 is connected a conductor 72, these conductors terminating in plugs a, b, c, d, e and f respectively, these plugs adapted to be inserted in any of the jacks, 55, 56, 57 or 58, according to the rate of wages which is assigned to any particular workman.

Attached to each of the conducting segments of the selecting commutator 59 is a

conductor 73 which passes to a switch 74. A conductor 75 connects the switch 74 with the electromagnetic device operating the clutch mechanism associated with a time register, as, for example, TA, this electromagnetic device being the same as that illustrated in detail in Figs. 2 and 3. The conductor 76 leads from the time register TA to the clutch actuating mechanism of the corresponding wage register, as WA. A conductor 77 leads from the latter clutch actuating mechanism to a plug, these plugs being designated respectively a^1 , b^1 , c^1 , d^1 , e^1 , and f^1 , for the different workmen. Conductors 78, similar to the conductor connecting the conducting segment of the selecting commutator 59 with the clutch actuating mechanism of the register TA, connect the segments B, C, D, E and F, with corresponding time registers TB, TC, TD, TE and TF, and conductors 76, similar to the conductor connecting the clutch actuating mechanisms of the registers TA and WA, connect the clutch actuating mechanism for the registers TB, TC, TD, TE and TF with the corresponding clutch actuating mechanisms for the wage registers WB, WC, WD, WE and WF. The plugs a^1 , b^1 , c^1 , d^1 , e^1 and f^1 are mounted in a plug-seat frame 78, and when the plugs are in the plugseats, they form a connection with the conductor 79 which leads from the plug seat frame 78 to the clutch actuating mechanism associated with the waste wage register WW. Associated with the plugs a^1 , b^1 , c^1 , d^1 , e^1 , and f^1 are a series of jacks, j^1 , j^2 , j^3 , j^4 , j^5 and j^6 , each of these series representing a single job. A conductor 80 leads from each series of jacks to the clutch actuating mechanism of its associated job register, the job registers J^1 , J^2 , J^3 , J^4 , J^5 and J^6 being thus brought into connection with the series of jacks j^1 , j^2 , j^3 , j^4 , j^5 and j^6 respectively. A conductor 81 leads from the clutch actuating mechanism associated with the job registers 45 between a clutch actuating mechanism associated with the total job register JT. A conductor 82 leads from the clutch actuating mechanism of the total waste wage register WW to the point 83 where it joins the conductor 84 leading from the clutch actuating mechanism associated with the total job register JT to the clutch actuating mechanism associated with the total wage register WT. A conductor 85 leads from the clutch actuating mechanism associated with the total wage register WT to a polarized clutch mechanism 86, the purpose of which will be described hereafter. A conductor 87 leads from the clutch actuating mechanism 86 to a portion of the shaft 29 which is in electrical connection with the disks 30 and 31. Rigidly mounted on the shaft 29 is the gear 88. In engagement with this gear and adapted to be actuated thereby is a gear 89 rigidly mounted on a shaft 90. Between the shaft 90 and the shaft 91 which is in line therewith, is a clutch 92 operated by means of an arm 93 connected with the armature 94 which is actuated by the electromagnetic mechanism 86. Rigidly mounted on the shaft 91 is a disk 95 provided with two notches 96 diametrically opposed to each other. The armature 94 is provided with a tooth 97 which is adapted to fit into either one of the notches 96. If the tooth 97 is not in one of the notches 96, the periphery of the disk 95 serves to hold the upper part of the armature 94, as shown in Fig. 1, to the right thereby causing the clutch 92 to stay in engagement and the shaft 91 is rotated with the shaft 90 until the tooth 97 has an opportunity to engage in one of the notches 96. Rigidly mounted on the shaft 91 are the bevel gears 98 and 99. In mesh with the bevel gear 98 are the bevel gears 100 and 101, rigidly mounted on the shafts 102 and 103 respectively. Mounted on the shaft 102 are the laterally slidable clutches 16 operated by the electromagnetic clutch actuating mechanisms associated with the registers WD, WE, WF, J^4 , J^5 and J^6 . Slidably mounted on the shaft 103 is a similar clutch 16 operated by the electromagnetic clutch actuating mechanism associated with the register WT. Similarly the bevel gears 104 and 105 are in mesh with the bevel gear 99, and are rigidly mounted on the ends of the shafts 106 and 107 respectively. The clutches 16 associated with the registers WA, WB, WC, J^1 , J^2 and J^3 are slidably mounted on the shaft 106 and the clutches 16 associated with the registers WW and JT, are slidably mounted on the shaft 107. An intermittent gear 108 is rigidly mounted on the shaft 29, the portion 109 of its periphery carrying teeth adapted to engage with the gear 110 rigidly mounted on the shaft 111. The portion 109 of the gear 108 has sufficient number of teeth to cause the gear 110 to be rotated one-half of a revolution each time that it is brought into engagement with the gear 110 by the rotation of the shaft 29. Rigidly mounted on the shaft 111 are the bevel gears 112 and 113. In mesh with the bevel gear 112 is the bevel gear 114, rigidly mounted on the end of the shaft 115. Slidably mounted on the shaft 115 are the clutches 16 associated with the time registers TD, DE and TF respectively. In mesh with the bevel gear 113 is the bevel gear 116 rigidly mounted on the end of the shaft 117. On the shaft 117 are slidably mounted the clutches 16 associated with the time registers TA, TB and TC respectively. The operation of my system may now be clearly understood. The time actuated shaft 29 is caused to revolve by suitable mechanism. While the brush 46 is in contact with the conducting portion of the im-

pulse making disk 32, it will be evident that the current will pass from the negative pole of the battery 39 through the conductor 45, the brush 46 and the disk 32 to the shaft 29. Let us now assume that the brush 53 comes in contact with the conducting portion of the disk 49. The current will therefore pass through this disk and the conductor 54 to the terminals associated with the jacks 55. Let us now assume that the plugs *a*, *b*, *c*, *d*, *e* and *f* are all inserted in the jacks 55; it is now evident that the current will successively pass through the conductors 72 associated with these plugs to the conducting segments A, B, C, D, E and F of the selecting commutator 60. The current passes through the brush 63, the brush holder 63, the shaft 61, the brush holder 62 and the brush 64 to the corresponding conducting segments of the selecting commutator 59, as shaft 61 is rotated. Let us assume that the brushes 64 and 65 are brought into contact with the conducting segments A; the current will then pass through the conductor 73 and the switch 74 to the clutch actuating mechanism associated with the time register TA and the clutch 16 will be brought into engagement with the gear 28 of the time register TA.

By means of the gear 108 and the portions 109 of its periphery, the shaft 111 will be rotated a half revolution during the time while the brushes 64 and 65 remain in contact with the conducting segments A and the time register TA will thereby be advanced one step. The current passes through the conductor 76 to the clutch actuating mechanism associated with the wage register WA. It is clear that the clutch 16 will remain in engagement with the gear 28 of this register as long as the brush 53 remains on the conducting portion of the rate disk 49. The shaft 91 is being rotated as long as the brush 46 remains in contact with the conducting portion of the impulse making disk 32, and it is, therefore evident that the wage register WA will be actuated an amount corresponding to the predetermined rate of wages represented by the peripheral length of the conducting portion of the disk 49. The current passes through the conductor 77 and if the plug *a'* is in its plug seat, the current passes through the conductor 79 to the clutch actuating mechanism associated with the waste wage register WW and the clutch 16 remains in engagement with the gear 28 of this register exactly the same length of time that the gear 16 associated with the wage register WA remains in engagement with the gear 28 of the latter register. The current passes through the conductor 82 and the conductor 84 to the clutch actuating mechanism associated with the total

wage register WT and the clutch 16 is similarly brought into engagement with the gear 28 of this register. The current then passes through the conductor 85 to the windings of the electromagnetic clutch 70 actuating mechanism 86 which serves to hold the armature 94 in a position by which the clutch 92 causes the shafts 90 and 91 to rotate together. From the electromagnetic actuating mechanism 86 the current 75 passes through the conductor 87 to the shaft 29, then through the conducting portion of the disk 30, the brush 43, and the conductors 41 and 40 back to the positive pole of the battery 39, thereby completing 80 the circuit.

If the plug *a'* instead of remaining in its plug seat is inserted in any of the jacks associated with the job registers, as, for example, *j'*, the current will pass through 85 the conductor 80 to the clutch actuating mechanism associated with the job register *J'* and will cause the clutch 16 to be brought into engagement with the gear 28 of this register for exactly the same time that the 90 clutches 16 are brought into engagement with the gears 28 of the registers TA and WA. The current then passes through the conductor 81 to the clutch actuating mechanism associated with the total job register 95 *JT*, and the clutch 16 is held in engagement with the gear 28 of this register. The current then passes through the conductor 84 and through the same path which has just 100 been described back to the positive pole of the battery 39.

It is evident from this description that the time and wage registers assigned to the various workmen A, B, C, D, E and F will be successively actuated and the job registers which are brought into electrical connection with the various wage registers, may be simultaneously actuated. The actuation of the various wage and job registers are all successively made in the total registers 110 WW or *JT* and WT so that the gears 28 of these registers are brought into engagement with the corresponding clutches for a time which is equal to the sums of the time the individual wage or job registers 115 are so connected.

From the foregoing description it is clear that although means are provided for bringing the clutches into engagement with the gears of the various registers, no means 120 are provided by which the clutches are removed from engagement. In order to accomplish this result an independent set of windings is provided for all of the clutch actuating mechanisms of the registers. The 125 conductor 118, connected with the conductor 87 at the point 119, is connected with independent windings on the polarized electromagnetic mechanism 86. Conductors 120 connect independent windings of all of the 130

clutch actuating mechanisms in series, and the conductor 121 then connects with the conductor 41 at the point 122. It is now clear that when the shaft 29 is rotated into 5 such position that the brushes 48 and 44 rest on the conducting portion of the peripheries of the disks 31 and 33 respectively, the brushes 43 and 46 meanwhile resting on the insulating segments of the peripheries of the 10 disks 30 and 32 respectively, the current will pass from the positive pole of the battery 39 through the conductors 45 and 47, the disk 31, the shaft 29, the conductors 87 and 118, through the windings of the electromagnetic 15 actuating mechanism 86 and then through the conductors 120 through all of the clutch actuating mechanisms associated with the registers back through the conductors 121, 41 and 40, to the negative pole of the battery 20 39, the current thus flowing through all of the clutch actuating mechanisms associated with the various registers in a direction opposite to that in which it passes while the brushes 43 and 46 remain in connection with 25 the conducting portions of the peripheries of the disks 30 and 32 respectively. In this way, on each revolution of the shaft 29, an impulse is sent through all of the clutch actuating mechanisms which tends to withdraw 30 the clutches from engagement with the gears of their corresponding registers. Let us now assume that none of the workmen are being employed and that, for instance, all 35 of the switches 74 are open. It is clear that under these circumstances no impulses will pass through the system tending to bring the clutches into engagement with the gears of the corresponding registers, but the impulses tending to withdraw the clutches 40 from such engagement will continue and all of the clutches will thereby be held in their disengaged positions. Under these circumstances the clutch 92 normally connecting 45 the shafts 90 and 91 will be held disengaged and the system of shafting connected with the various registers will, for this reason, not be operated.

It has been assumed that all of the plugs *a, b, c, d, e* and *f* are inserted in the jacks 55 50 but it is evident that where different workmen are employed at different rates of wages, these plugs may be inserted in suitable jacks, 55, 56, 57 or 58 and connection will thereby be made with the battery 59 55 through the disks 49, 50, 51 or 52, but for varying lengths of time according to the peripheral lengths of the conducting portions of these rate disks. The successive 60 actuations will pass through the system exactly according to the method which I have described and the actuations will be totalized in appropriate totalizing registers.

In order to avoid needless complication of the system which I have described, no method 65 has been shown in the drawings by which

the registers may be decumulated, but it is clear that such decumulation could readily be accomplished either by reversing the direction of rotation of the shaft 29 or suitable reversing gears and clutches could be provided in connection with the various individual registers.

It is evident that many changes could be made in the detailed construction of the system which has been described without departing from the spirit of my invention.

What I claim as new and desire to cover by United States Letters Patent is:

1. In combination, a plurality of wage registers, mechanical means for actuating said registers, electromagnetic means associated with each register for operatively connecting each register with said actuating means, means for successively energizing said connecting means of said registers for periods of time proportional to predetermined rates of wages, a total register, electromagnetic means for connecting said total register with said actuating means, and means for energizing said connecting means on the energization of the connecting means of any of the individual registers.

2. In combination, a plurality of accounting registers, common means for actuating said registers, electrical means associated with each register for intermittently connecting said register with said actuating means, and means for periodically disconnecting said register from said actuating means.

3. In combination, a plurality of accounting registers, a shaft for actuating said registers, a clutch for each of said registers, said clutch adapted to engage said register with said shaft, electromagnetic means for engaging said clutch with said register, and electromagnetic means for periodically disengaging said clutch from said register.

4. In an accounting system, a wage register, a job register, a mechanical source of power for actuating said registers, electromagnetic means associated with each register for mechanically connecting said register with said source of power, and means for electrically joining said electromagnetic connecting means, thereby causing simultaneous actuations of said wage and said job registers.

5. In an accounting system, a plurality of wage registers, a plurality of job registers, a source of mechanical power for actuating said registers, electromagnetic means associated with each register for mechanically connecting said register with said source of power, means for electrically connecting any of said wage registers with any of said job registers, and means for successively energizing the electromagnetic connecting means associated with said wage registers.

6. In an accounting system, a wage regis-

ter, a job register, a source of mechanical power for actuating said registers, electromagnetic means associated with each register for mechanically engaging said register with said source of power, means for energizing said electromagnetic means for a period of time proportional to a predetermined rate of wages, and means for electrically connecting said electromagnetic engaging means, thereby causing simultaneous actuations of said wage and said job registers.

7. In an accounting system, a plurality of wage registers, a plurality of job registers, 15 a source of mechanical power for actuating said registers, electromagnetic means associated with each register for mechanically engaging said register with said source of power, means for electrically connecting any 20 of said wage registers with any of said job registers, and means for successively energizing the electromagnetic engaging means associated with said wage registers for periods of time proportional to predetermined 25 rates of wages.

8. In an accounting system, the combination of a register, time controlled devices for actuating said register, electric means for intermittently engaging said register 30 with said actuating means, and means for periodically operating said actuating means.

9. In an accounting system, the combination of a register, time controlled devices for actuating said register, electric means for intermittently engaging said register 35 with said actuating means, means for periodically operating said actuating means, and means for periodically disengaging said register from said actuating means.

10. In an accounting system, a time register, a wage register, a source of mechanical power, an actuating shaft associated with each register, electromagnetic means for engaging each register with its associated 45 shaft, means for periodically mechanically connecting the shaft associated with the time register to said source of power during a predetermined length of time, said register thereby being actuated by constant increments, and means for mechanically connecting the shaft associated with the wage 50 register to said source of power, the actuations of said wage register thereby being proportional to the length of time said register is connected to said actuating shaft.

11. In an accounting system, the combination of a register, actuating mechanism, polarized connecting mechanism, controlling mechanism, and circuit connections from the 60 polarized connecting mechanism to the controlling mechanism, such controlling mechanism adapted to send a first impulse over the circuit connections to operatively connect the register and actuating mechanism 65 and when desired to send a second impulse

over such connections to disconnect the actuating mechanism from the register.

12. In an accounting system, the combination of a register, actuating mechanism, polarized connecting mechanism, controlling mechanism, a connecting circuit, and a disconnecting circuit, energization of the connecting circuit by the controlling means serving to operatively connect the actuating mechanism and the register and energization of the disconnecting circuit by the controlling means serving to disconnect the register from the actuating mechanism. 75

13. In an accounting system, the combination of a register, a time-controlled shaft, 80 a driving gear, controlling mechanism, and circuit connections extending from the controlling mechanism, such controlling mechanism adapted to send a first impulse over the circuit connections to move the driving gear to operatively connect the register and shaft and when desired to send a second impulse over such connections to move the driving gear to an inoperative position. 85

14. In an accounting system, the combination of a register, a time-controlled shaft, a driving gear, controlling mechanism, a connecting circuit, and a disconnecting circuit, energization of the connecting circuit by the controlling means serving to 90 move the driving gear to operatively connect the shaft and the register and energization of the disconnecting circuit by the controlling means serving to move the driving gear to an inoperative position. 95

15. In an accounting system, the combination of a register, a time-controlled shaft, a driving gear, controlling mechanism, and circuit connections extending from the controlling mechanism, such controlling mechanism adapted to send a first impulse over the circuit connections to move the driving gear to operatively connect the register and shaft and when desired to send a second impulse over such connections to move the driving gear to an inoperative position, such gear adapted to remain in either position unless moved to the other position by means of a current impulse from the controlling mechanism. 100

16. In an accounting system, the combination of a register, a time-controlled shaft, a driving gear, controlling mechanism, a connecting circuit, and a disconnecting circuit, energization of the connecting circuit by the controlling means serving to move the driving gear to operatively connect the shaft and the register and energization of the disconnecting circuit by the controlling means serving to move the driving gear to 105 an inoperative position, such gear adapted to remain in either position unless moved to the other position by means of a current impulse from the controlling mechanism. 110

17. In an accounting system, the combination

- tion of a register, a time-controlled shaft, a polarized driving gear, controlling mechanism, and circuit connections extending from the controlling mechanism such controlling mechanism adapted to send a first impulse over the circuit connections to move the driving gear to operatively connect the register and shaft and when desired to send a second impulse over such connections to move the driving gear to an inoperative position.
18. In an accounting system, the combination of a register, a time-controlled shaft, a polarized driving gear, controlling mechanism, a connecting circuit, and a disconnecting circuit, energization of the connecting circuit by the controlling means serving to move the driving gear to operatively connect the shaft and the register and energization of the disconnecting circuit by the controlling means serving to move the driving gear to an inoperative position.
19. In an accounting system, the combination of a register, a time-controlled shaft, a driving gear, an electromagnetic device adapted to move the driving gear into or out of operative position, and circuit connections extending from the electromagnetic device, a first impulse over such connections serving to move the driving gear to connect the register and the shaft and a second impulse over such connections serving to move the driving gear to an inoperative position.
20. In an accounting system, the combination of a register, a time-controlled shaft, a driving gear, an electromagnetic device adapted to move the driving gear into or out of operative position, a connecting circuit, and a disconnecting circuit, the energization of the connecting circuit serving to move the driving gear to a position to operatively connect the shaft and register and energization of the disconnecting circuit serving to move the driving gear to an inoperative position.
21. In an accounting system, the combination of a wage register, a waste wage register, actuating mechanism, connecting devices, controlling mechanism, and circuit connections from the connecting devices to the controlling mechanism, such controlling mechanism adapted to send a first impulse over the circuit connections to operatively connect the registers and the actuating mechanism and when desired to send a second impulse over such connections to disconnect the actuating mechanism from the registers.
22. In an accounting system, the combination of a wage register, a waste wage register, actuating mechanism, connecting devices, and circuit connections extending from the connecting devices, a first electric impulse over the circuit connections serving to operatively connect the registers and the actuating mechanism and a second electric impulse over such connections serving to disconnect the actuating mechanism from the registers.
23. In an accounting system, the combination of a wage register, a waste wage register, actuating mechanism, connecting devices, a connecting circuit, and a disconnecting circuit, energization of the connecting circuit serving to operatively connect the actuating mechanism and the registers and energization of the disconnecting circuit serving to disconnect the registers from the actuating mechanism.
24. In an accounting system, the combination of a wage register, a job register, a waste wage register, actuating mechanism, connecting devices, and circuit connections extending from such connecting devices, a first electric impulse over the circuit connections serving to operatively connect the actuating mechanism with the wage register and also with either the job register or the waste wage register and a second electric impulse over such connections serving to disconnect the registers previously connected to the actuating mechanism.
25. In an accounting system, the combination of a wage register, a job register, a waste wage register, connecting devices, a connecting circuit, and a disconnecting circuit, energization of the connecting circuit serving to operatively connect the actuating mechanism with the wage register and either with the job register or the waste wage register as desired and energization of the disconnecting circuit serving to disconnect the previously connected registers from the actuating mechanism.
26. In an accounting system, the combination of a wage register, a job register, a waste wage register, a wage totalizing register, actuating mechanism, connecting devices, and circuit connections extending from the connecting devices, a first electric impulse over the circuit connections serving to connect the actuating mechanism with the wage register and the wage totalizing register and also with either the job register or the waste wage register as desired and a second electric impulse over such connections serving to disconnect the previously connected registers from the actuating mechanism.
27. In an accounting system, the combination of a wage register, a job register, a waste wage register, a wage totalizing register, actuating mechanism, connecting devices, a connecting circuit, and a disconnecting circuit, energization of the connecting circuit serving to operatively connect the actuating mechanism with the wage register and the wage totalizing register and also with either the job register or the waste wage register as desired and energization of

the disconnecting circuit serving to disconnect the previously connected registers from the actuating mechanism.

28. In an accounting system, the combination of a wage register, a time register, actuating mechanism, connecting devices, and circuit connections extending from the connecting devices, a first impulse over the circuit connections serving to operatively connect the registers and the actuating mechanism and a second electric impulse over such connections serving to disconnect such registers from the actuating mechanism.

29. In an accounting system, the combination of a wage register, a time register, actuating mechanism, connecting devices, a connecting circuit, and a disconnecting circuit, energization of the connecting circuit serving to operatively connect the actuating mechanism and the registers and energization of the disconnecting circuit serving to disconnect the registers from the actuating mechanism.

30. In an accounting system, the combination of a plurality of wage registers, a wage totalizing register, actuating mechanism, connecting devices, and circuit connections extending from the connecting devices, electric impulses of a first kind over the circuit connections serving to operatively connect one or more of the wage registers and the wage totalizing register with the actuating mechanism and electric impulses of a second kind over such connections serving to disconnect the previously connected registers from the actuating mechanism.

31. In an accounting system, the combination of a plurality of wage registers, a wage totalizing register, actuating mechanism, connecting devices, connecting circuits, and disconnecting circuits, energization of the connecting circuits serving to operatively connect the corresponding wage registers with the actuating mechanism and energization of the disconnecting circuits serving to disconnect the previously connected registers from the actuating mechanism.

32. In an accounting system, the combination of a register, actuating mechanism, connecting mechanism, circuit connections extending from the connecting mechanism, a first electric impulse over the circuit connections serving to operatively connect the register and actuating mechanism and a second electric impulse over such connections serving to disconnect the actuating mechanism from the register, and means for automatically starting the actuating mechanism when the register is operatively connected.

33. In an accounting system, the combination of a register, actuating mechanism, connecting mechanism, circuit connections extending from the connecting mechanism, a first electric impulse over the circuit connections serving to operatively connect the

register and actuating mechanism and a second electric impulse over such connections serving to disconnect the actuating mechanism from the register, and means for automatically stopping the actuating mechanism when the register is disconnected therefrom.

34. In an accounting system, the combination of a register, actuating mechanism, connecting mechanism, circuit connections extending from the connecting mechanism, a first electric impulse over the circuit connections serving to operatively connect the register and actuating mechanism and a second electric impulse over such connections serving to disconnect the actuating mechanism from the register, means for automatically starting the actuating mechanism when the register is operatively connected, and means for automatically stopping the actuating mechanism when the register is disconnected therefrom.

35. In an accounting system, the combination of a register, actuating mechanism, connecting mechanism, circuit connections extending from the connecting mechanism, a first electric impulse over the circuit connections serving to operatively connect the register and actuating mechanism and a second electric impulse over such connections serving to disconnect the actuating mechanism from the register, and variable rate mechanism adapted to be included in the circuit connections to actuate the register at a desired rate.

36. In an accounting system, the combination of a wage register, a plurality of job registers, actuating mechanism, connecting devices, and circuit connections extending from the connecting devices, a first electric impulse over the circuit connections serving to operatively connect the wage register and a desired one of the job registers with the actuating mechanism and a second electric impulse over such connections serving to disconnect the previously connected registers from the actuating mechanism.

37. In an accounting system, the combination of a wage register, a plurality of job registers, actuating mechanism, connecting devices, circuit connections extending from the connecting devices, a first electric impulse over the circuit connections serving to operatively connect the wage register and a desired one of the job registers with the actuating mechanism and a second electric impulse over such connections serving to disconnect the previously connected registers from the actuating mechanism, and means for including in the circuit connections a desired one of the job registers.

38. In an accounting system, the combination of a wage register, a plurality of job registers, a waste wage register, actuating mechanism, connecting devices, circuit connections extending from the connecting de-

5 vices, a first electric impulse over the circuit connections serving to operatively connect the wage register and a desired one of the job registers with the actuating mechanism and a second electric impulse over such connections serving to disconnect the previously connected registers from the actuating mechanism, means for including in the circuit connections of the wage register a 10 desired one of the job registers, and means for automatically including in the circuit connections of the wage register the waste wage register when the wage register is disconnected from the job register.

15 39. In an accounting system, the combination of a wage register, a job register, a waste wage register, actuating mechanism, connecting devices, circuit connections extending from such connecting devices, a first 20 electric impulse over the circuit connections serving to operatively connect the actuating mechanism with the wage register and also with either the job register or the waste 25 wage register and a second electric impulse over such connections serving to disconnect the registers previously connected to the actuating mechanism, and means for automatically including in the circuit connections of the wage register the waste wage 30 register when the wage register is disconnected from the job register.

40 40. In a register, the combination of indicating mechanism, actuating mechanism, a polarized device adapted to connect the 35 indicating mechanism and the actuating

mechanism or to disconnect the same as desired, an electromagnetic mechanism for moving the connecting device from either of its positions to the other according to the direction of magnetization of such electromagnetic mechanism. 40

41. In a register, the combination of indicating wheels, an actuating shaft, a gear carried by the shaft and movable into engagement with the indicating wheels or out of engagement therewith as desired, and electromagnetic mechanism for moving the gear from either position to the other. 45

42. In a register, the combination of indicating wheels, an actuating shaft, a polarized gear carried by the shaft and movable into engagement with the indicating wheels or out of engagement therewith as desired, and electromagnetic mechanism for moving the gear from either position to the other 50 55 according to the direction of magnetization of such electromagnetic mechanism.

43. In a register, the combination of indicating mechanism, an actuating member, and electromagnetic mechanism adapted to move the actuating member either to engage the indicating mechanism or to disengage the same as desired. 60

In witness whereof, I hereunto subscribe my name this 25th day of June, A. D. 1909. 65

WILLIAM J. CRUMPTON.
